ROLL-OVER TOY

Willis E. Rexford, Girard, Pa., assignor to Louis Marx & Company, Inc., New York, N. Y., a corporation of New York

Application April 1, 1939, Serial No. 265,390

22 Claims. (Cl. 46—103)

This invention relates to toys, more especially a roll-over toy, and still more particularly to a running toy which rolls over at intervals as it runs along.

5 The primary object of my invention is to generally improve toys, and to provide a toy of the specified character. A more specific object is to provide mechanism for causing the desired roll-over action, which mechanism is inconspicuous 10 and does not detract from the realism of the action of the toy. Another object is to so arrange the toy that it changes direction each time that it rolls over. Still another object is to provide a simple and inexpensive mechanism for causing 15 intermittent action of the roll-over mechanism, thereby affording opportunity for the toy to run along for some distance before again rolling over. Still another object is to embody the toy in the form of a dog which simulatedly runs 20 along, rolls over and again runs along and rolls over until the motor is unwound, the reaction member for causing the rolling of the dog being so designed as to simulate the tail of the dog.

Another object of my invention is to embody 25 the toy in the form of an airplane which simulatedly performs a barrel roll, preferably accompanied by a sharp change in direction. Inasmuch as the wings project from the fuselage for a substantial distance at the forward end, compared to the tail at the rear end, the desired 30 change in direction is readily obtained during the barrel roll. However, the said wing spread also makes it difficult for the airplane to roll over, and an ancillary object of my invention is to facilitate 35 this rolling over of the airplane, and for this purpose, I provide substantial projections at the top and bottom of the fuselage.

A more specific object of the invention is to 40 provide a reaction member which bears on the floor for a substantial distance. For this purpose, the end of the reaction member is preferably bent forwardly at a point far enough from the body to rotatively clear the same, and the angle at which it is bent forward is made such 45 that it rests flat on the floor when it is rolling the toy over.

Still another object of the invention is to provide means for holding the reaction member off 50 the floor when the toy is running forward. This refinement is not essential, but it is desirable in order to prevent the reaction member from impeding the progress of the toy if the toy is operated on a thick carpet or a rough surface. For 55 this purpose, the drive between the motor and the reaction member is made intermittent by

using a mutilated gear, and the mutilated part of the gear is so dimensioned as to lock the gear driven thereby against rotation during its dwell period.

To the accomplishment of the foregoing and other objects which will hereinafter appear, my invention consists in the toy elements and their relation one to the other, as hereinafter are more particularly described in the specification, and sought to be defined in the claims. The specification is accompanied by drawings in which:

Fig. 1 is a side elevation of a toy embodying features of the invention;

Fig. 2 is a longitudinal section taken in elevation through the toy;

Fig. 3 is a bottom plan view of the toy;

Fig. 4 is explanatory of the operation of the toy;

Fig. 5 is a side elevation of a toy airplane embodying features of my invention.

Fig. 6 is a bottom view of a part of the airplane;

Fig. 7 is an elevation of a special gear used in the airplane, looking in the plane of the line 7—7 of Fig. 6;

Fig. 8 is a section taken through the gear, looking in the plane of the line 8—8 of Fig. 7;

Fig. 9 is a diagram explanatory of the operation of the toy airplane;

Fig. 10 is a front elevation of a modified airplane toy embodying further features of my invention;

Fig. 11 is a side elevation of the motor used in the airplane of Fig. 10; and

Fig. 12 is a transverse section, taken in the plane of the line 12—12 of Fig. 11.

The invention is disclosed in three forms. In the first form, the roll-over toy simulates a dog, and this form of the invention is shown in Figs. 1 through 4 of the drawings. In the second form, 40 the toy simulates an airplane, and this form of the invention is illustrated in Figs. 5 through 9 of the drawings. In the third form, the toy also simulates an airplane, this being illustrated in Figs. 10, 11 and 12 of the drawings.

Referring to the first form of the invention, and more particularly to Fig. 1, the toy comprises a preferably elongated body 12 provided with preferably inconspicuous and nearly concealed wheels 14 and 16. A reaction member 18 is disposed alongside the toy and is connected to the shaft 20 which extends longitudinally of the toy and projects from the rear end thereof. In the present case, the reaction member 18 and shaft 20 are made by bending a single continuous piece 55

of wire, and the said piece of wire simulates the tail of the dog.

Referring now to Figs. 2 and 3, the toy is provided with concealed motor works generally designated 22. This includes a spring motor which is of conventional character, in that it comprises a square winding stem 24 and a spiral ribbon spring 26, the outer end 28 of the spring being connected to the motor frame and the inner end 10 being connected to the winding stem 24. The motor is provided with a train of step-up gearing for driving the rear wheels 14. Specifically, the winding stem 24 carries a main gear 30 meshing with a pinion 32, which is secured to an intermediate gear 34, which in turn meshes with a pinion 36 carried by the axle 38 of wheels 14. The wheels are, of course, secured to the axle and rotated thereby.

The motor may be wound by a key 40 which 20 may be applied to one end of winding stem 24 through an appropriate hole in the side of the toy body. The motor may, of course, include the usual ratchet or clutch mechanism to permit winding the spring without driving the gears and 25 wheels. If desired, the motor may be provided with a speed limiting device or governor which, in the present case, comprises a weight 42 carried on an arm 44 which is oscillatable about the axle 38. Axle 38 carries a gear 46 meshing with a 30 pinion 48, said pinion carrying an eccentric 50, which eccentric is received in a mating slot in arm 44. It will be evident that as the motor unwinds the weight 42 is reciprocated at very high speed by the eccentric 50, and this limits the 35 winding speed of the motor.

The motor is provided with another gear train leading to the shaft 20. More specifically, the winding stem 24 carries a mutilated gear 52. This meshes with an idler pinion 54, which in 40 turn meshes with a crown gear 56, the latter being secured to the inner end of shaft 20. It will be evident that during unwinding of the motor, the shaft 20 is rotated, but at a speed much slower than the speed of the driving wheels 14. Moreover, the rotation of shaft 20 is intermittent, for 45 the shaft dwells when the mutilated parts 58 of gear 52 reach the pinion 54. The number of teeth left on mutilated gear 52 is preferably so selected as to produce one complete revolution, 50 or a little less than one complete revolution of shaft 20, thus bringing the toy from upright position back to upright position again. In the present case, the teeth have been divided into two parts, so that there is a dwell during the rolling 55 over of the toy. However, the teeth may be combined so as to produce one continuous rolling over of the toy, or on the other hand, the size of the gear and the number of teeth in each portion may be increased, so that there will be more 60 than one rolling over and forward running operation of the toy for each rotation of the winding stem.

The construction of the body of the toy is relatively unimportant, but it may be mentioned 65 that, in the present case, the body 12 is made of two oppositely dished halves of sheet metal which are secured together in edge to edge relation by appropriate tongue connections passing through washers, this being indicated at 60. The bottom 70 of the toy is closed by a bottom plate 62, this being secured to the sides by conventional tongue and slot connections as is indicated at 64. The front wheel 16 turns on a pin 66 which is carried by lugs 68 bent upwardly from the bottom 62 of 75 the toy. The motor 22 includes a frame which is

secured to the bottom plate 62 by appropriate tongue and slot connections 70. The bottom plate 62 is, of course, cut away as is indicated at 72 to clear the driving wheels 14. A part of the bottom has been broken away beneath the motor in Fig. 3, in order to expose the parts of the motor. The shaft 20 is carried at its inner end by the motor frame, and is additionally carried by a small bearing plate 74, which may also be used as a connector plate or washer for securing the 10 halves of the body together.

It may be pointed out that the body is larger in dimension at one end than at the other. Specifically, in the present case, the vertical dimension of the body at the top of the head or at the 15 point 76 (Fig. 1) is substantially greater than at the rear end of the body, say, at the point 78. This causes the toy to change direction each time it rolls over as is hereinafter described.

The operation of the toy will be clear from examination of Fig. 4. The toy may be assumed to be initially running in the direction 80. The tail or reaction member 18 rests loosely on the floor as the toy runs along. At this time, no rotative force is applied to the member 18. When the toy reaches the position 82, it begins to roll over, this being caused by the fact that a toothed part of the mutilated gear has come into mesh, thereby applying a rotative force to member 18. The direction of this rotative force is such as to tend to force member 18 downwardly, but inasmuch as it is already resting on the floor, the toy instead rolls over on one side, as is indicated at 84. It continues to roll over to an upside down position (not shown), and rolls further to a position on the opposite side, as is indicated at 86. If the mutilated gear is cut away at this point, the toy rolls over freely it being unstable in the upside down position, and the toy dwells or rests on its side for a time in the position 86. When the teeth 40 of the mutilated gear again come into action, the toy is rolled further, and finally comes again to the upright position indicated at 88. During the rolling operation, the driving wheels 14 are rotating, but no forward movement of the toy takes 45 place, for the wheels are not on the ground. On reaching the position 88, however, the driving wheels are again on the ground and the toy runs forwardly, as is indicated by the line 90. At this time no torque is applied to the reaction member 18, for a toothless part of the mutilated gear has again been reached. The toy runs along to the position 92, at which time a toothed part of the mutilated gear is again reached and the toy again rolls over, as is indicated by the successive positions 94, 96, 98. The toy then again runs forwardly, as is indicated at 100, and when a toothed part of the mutilated gear is again reached, the toy again rolls over, as is indicated by the successive positions 102, 104, 106, 108.

It will be observed that because of the construction of the toy body, the direction lines 80, 90 and 100 are angularly related to one another, so that the toy in the course of its continuous operation may describe a complete circle, 65 and thus be operating within the confines of a single room.

Reverting to Figs. 1, 2 and 3 attention may be directed to the stud 110 projecting from the bottom of the toy near one edge, specifically, the 70 edge opposite the reaction member 18. This stud is not essential, but in some cases may prove desirable. Its object is to prevent the toy from rolling over more than a full revolution, or from continuing its rolling action past upright posi- 75

tion under its own inertia. In the present case, the toy has only three wheels and the two rear wheels are rather close together. The toy, therefore, rests somewhat unstably on the three wheels, and if the turning force bringing the toy to upright position is great, the toy may continue rolling past the desired upright position. The stud 110 adds stability to the toy and makes it more difficult for the toy to accidentally roll past the desired upright position.

Referring now to Figs. 5 through 9 of the drawings, the toy there shown simulates an airplane comprising a fuselage 112 with a pair of wings 114 projecting sidewardly therefrom. The fuselage runs on main driving wheels 116 and a tail wheel 118. The wheels 116 are carried in a motor frame 120 which preferably projects a substantial distance beneath the fuselage. The rear end of the fuselage is provided with a tail 122 and an upstanding surface 124 simulating a rudder. A further projection 126 is provided at the top of the fuselage to facilitate rolling over of the airplane despite the sidewardly extending wings 114. In the present case, the projection 126 simulates the head of a pilot.

The reaction member is indicated at 130. This consists of a single piece of wire, the inner end 132 of which is rotatably mounted in the airplane 30 and extends in the direction of the axis of the fuselage. The wire is bent sidewardly at 134 an amount sufficient to clear the tail 122 and the rudder 124 of the airplane. The part 130 is bent forwardly and is disposed in such a direction that it normally rests flat on the floor or running surface, or in other words, bears upon the floor over its entire length when it is operating to roll the airplane over. The desired angle may be determined by experiment, but as a rough 40 guide, it may be said that the part 130 should extend approximately in the direction of the tip of wing 114. As before, the wheels 116 are preferably driven continuously, while the reaction member 130 is driven only intermittently. Referring to Fig. 6, the motor comprises a preferably square winding stem 136 about which is wound a conventional main spring 138. This in turn drives a mutilated gear 140 the teeth of which mesh with a pinion 142, which in turn 50 drives a gear 144 meshing with a pinion 146 mounted directly on the axle 148 which carries the wheels 116. If desired, the unwinding speed of the motor may be limited by suitable governor mechanism such as an escapement plate 150 oscillated by the teeth of an escapement wheel 152 mounted on axle 148.

A separate gear train is provided for the reaction member. This includes the mutilated main gear 140 meshing with an idler or intermediate pinion 154 which in turn meshes with a crown gear 156 secured to the inner end of the shaft or wire 132 carrying the reaction member. The pinion 154 is comparatively short, and is so located that a part of gear 140, namely the part 65 158, meshes with pinion 154, whereas another part, namely the part 160, clears the end of pinion 154 and does not drive the same. In this respect the comparatively short pinion 154 is to be contrasted with the long pinion 142 in the 70 gear train leading to axle 148, for either of the parts 158 or 160 meshes with the long pinion 142, hence the drive of the axle is continuous.

The construction of mutilated gear 140 may be further explained with reference to Figs. 7 and 8, in which it will be seen that the gear com-

prises a disc of sheet metal 162, a part of the periphery of which is drawn or displaced sidewardly. Both the flat and displaced parts of the gear are cut to provide a continuous series of gear teeth, as will appear from inspection of Fig. 7, but some of these teeth are displaced sidewardly, as at 158 in Fig. 8, while others are not, as at 160. It happens that in the specific form here shown, there are two displaced sections corresponding to two running periods and two rolling-over periods, for each complete revolution of the winding stem 136. However, the operating principle is, of course, the same as if there were only one displaced section.

Referring now to Fig. 9, the toy runs forward, 15 as is indicated by the line 164, until the teeth 158 of the mutilated gear come into action, at which time the reaction member 130 bears downwardly against the floor and causes the airplane to roll over, as is indicated by the successive positions 166, 168, 170, 172 and 174, at which time the airplane is again right side up on its running wheels. While rolling over, the toy has changed substantially in direction, and in the specific case here shown, the airplane next runs in the direction of line 176, which is approximately at right angles to the original direction line 164. The toy proceeds along the line 176 until the side-displaced teeth 158 of the mutilated gear again come into mesh with the idler pinion 142, 30 at which time the airplane is again caused to roll over, this being indicated by the successive positions 178, 180 and 182. The number of teeth in the mutilated gear is, of course, so selected as to bring the airplane back to upright position 35 on its running wheels, whereupon the toy again runs forward in the new direction, as is indicated by the direction line 184.

Another form of toy airplane is illustrated in Fig. 10. In this case the airplane simulates a 40 modern airplane with an enclosed cabin 186. If this cabin does not provide sufficient projection above the fuselage to facilitate rolling over of the airplane, the airplane may be provided with an arcuately bent piece of wire 188 extending substantially from wing tip to wing tip. This wire is not as conspicuous as it appears in Fig. 10, because when looking at the toy from any other direction, the wings 190 have broad, extensive surfaces, whereas the member 188 is a mere wire. 45

The airplane of Fig. 10 illustrates a much more important feature, which feature is applicable to all forms of roll-over toy including, for example, the animal or dog toy first described. I am referring to the fact that the reaction member 192 does not rest on the floor or running surface 194 when the toy is running forward on its wheels 196. Instead, the reaction member 192 is supported above the floor and in no way impedes the progress of the toy. 55

One preferred way in which this may be done is described with reference to Figs. 11 and 12 of the drawings, which are respectively side and end elevations of the motor used in the airplane of Fig. 10. This motor comprises a main winding stem 200 carrying a conventional ribbon or spiral spring 202, the inner end of which is secured to the winding stem, and the outer end 204 of which is secured to the frame 206 of the motor. The main stem 200 carries a gear 208 for driving 65 the axle 210 of wheels 196. Specifically, gear 208 meshes with a pinion 212 which is secured to a gear 214 meshing with a pinion 216 mounted directly on axle 210. If desired, the speed of the motor may be limited by suitable governor 70 75

mechanism which in the present case is like that already described in connection with Figs. 2 and 3. Specifically, it consists of a gear 218 on axle 210, meshing with a pinion 220, which in 5 turn rotates an eccentric 222 riding within a slot 224 cut through an oscillatable member 226 which in the present case is pivoted for free oscillation on axle 210.

A completely separate gear train is provided 10 for intermittently rotating the reaction member 192. Specifically, the winding stem 200 carries a crown gear 230 (Fig. 11) which meshes with a pinion 232. Pinion 232 is carried on a shaft 234 extending longitudinally of the toy, and in the 15 present case, just outside the side plate of the motor frame. The side plate is cut away at 236 to provide access between crown gear 230 within the frame, and gear 232 much of which is outside the frame.

20 At its rear end the shaft 234 carries a mutilated gear 238. This meshes with a pinion 240 mounted at the inner end of a shaft 242 which extends longitudinally of the fuselage and projects rearwardly therefrom. Actually, the shaft 242 and the reaction member 192 may consist of a single piece of wire appropriately bent, but functionally, it may be said that reaction member 192 at the side of the toy is connected to shaft 242 carrying the pinion 240.

30 Mutilated gear 238 has enough teeth to produce one revolution of the reaction member. The remainder of mutilated gear 238 is devoid of teeth and this mutilated part of the gear corresponds to a dwell period for the reaction member. It is 35 very important to note, however, that in the present case the teeth are not cut away to their full root depth. Instead, the portion 244 is made of such radius that it bears against two of the teeth of pinion 240, as shown in the drawings, and 40 prevents rotation of the pinion. The action is equivalent to that used in typical Geneva gear mechanism or transfer mechanism for counters and the like, in that driving gear 230 produces only intermittent movement of the driven pinion 45 240, and between movements, the pinion 240 is locked against movement by the gear 238. Of course, the full root depth is used at the ends of the portion 244, as is indicated at 246, for otherwise the gears would lock at that point.

50 It is obvious that by properly rotatively relating the reaction member 192 to the pinion 240, the locked position of the pinion may be made to correspond to the desired elevated position of the reaction member, so that the reaction member 55 is held off the floor, as illustrated in Fig. 10. Moreover, the reaction member may be held somewhat higher, as when simulating the tail of an animal, but, of course, it must be brought down far enough to successfully complete the rolling 60 over of the toy onto its running wheels. The exact point at which the movement of the reaction member may be stopped depends on the configuration and balance of the particular toy, for the last part of the movement of the toy onto its 65 wheels will take place automatically after the toy has been moved to nearly upright position.

It is believed that the construction and operation, as well as the advantages of my improved toy, will be apparent from the foregoing detailed 70 description thereof. It will also be apparent that while I have shown and described my invention in several preferred forms, many changes and modifications may be made in the structures disclosed, without departing from the spirit of the 75 invention defined in the following claims.

I claim:

1. A toy comprising a toy body, a reaction member outside said body and connected to a shaft which projects from the body, and a motor in said body for rotating said shaft and thereby causing the body to roll over on the floor, said reaction member bearing against the floor and clearing said body during complete rotation of the body relative to the reaction member. 5

2. A toy comprising a toy body, a reaction member outside said body and connected to a shaft which projects from one end of the body and extends longitudinally of the same, said reaction member and said body clearing one another during complete relative rotation of said 10 member and said body, and a motor in said body for rotating said shaft to cause the reaction member to bear against the floor and thereby causing the body to roll over on the floor. 15

3. A toy comprising a toy body, a reaction member at the side of said body connected to a shaft which projects from one end of the body and extends longitudinally of the same, and a motor in said body for rotating said shaft to cause the reaction member to bear against the floor and thereby causing the body to roll over on the floor, said body being larger at one end than the other so that the direction of the body 20 changes as it rolls over. 25

4. A toy comprising a toy body, wheels at the bottom of said body, a reaction member outside said body and connected to a shaft projecting from the body, said reaction member and said body clearing one another during complete relative rotation of said member and said body, and a motor in said body for driving the aforesaid wheels and the aforesaid shaft, said reaction member being so positioned relative to said shaft that it bears against the floor and clears said body during rotation of the body. 30

5. A toy comprising a toy body, wheels at the bottom of said body, a reaction member outside said body and connected to a shaft projecting from the body, and a motor in said body for driving the aforesaid wheels and the aforesaid shaft, the gear train leading to the shaft including means to make the rotation of the shaft intermittent, said reaction member being so positioned relative to said shaft that it bears against the floor and clears said body during complete rotation of the body relative to the reaction member. 45

6. A toy comprising a toy body, wheels at the bottom of said body, a bent wire reaction member outside said body and connected to a shaft projecting from one end of the body and extending longitudinally of the same, said reaction member and said body clearing one another during complete relative rotation of said member and said body, and a motor in said body for driving the aforesaid wheels and the aforesaid shaft, the gear train leading to the shaft including a mutilated gear so that the rotation of the shaft is intermittent. 55

7. A toy comprising a toy body, wheels at the bottom of said body, a wire reaction member at one side of said body connected to a shaft projecting from the body, and a motor in said body for driving the aforesaid wheels and the aforesaid shaft, the gear train leading to the shaft including means to make the rotation of the shaft 70 intermittent, said body being larger at one end than the other so that the direction of the body changes as it rolls over. 75

8. A toy simulating an animal body, a wire projecting from the rear end of the body and 75

- bent to a sideward position, said wire simulating a tail and being so shaped that it rotationally clears the body during complete relative rotation, but does not clear the floor, the end of the wire which projects into the rear end of the toy being rotatably mounted, and a motor in the toy body geared to said wire for rotating the same and thereby causing the animal to simulatedly roll over on the floor.
10. A toy simulating an animal body, a wire projecting from the rear end of the body and bent to a sideward position, said wire simulating a tail and being so shaped that it rotationally clears the body during complete relative rotation, but does not clear the floor, the end of the wire which projects into the rear end of the toy being rotatably mounted, a motor in the toy body geared to said wire for rotating the same, and thereby causing the animal to simulatedly roll over on the floor, and means in said gearing to make the rolling action intermittent.
15. A toy simulating an animal body, a wire projecting from the rear end of the body and bent to a sideward position, said wire simulating a tail and being so shaped that it rotationally clears the body but not the floor, the end of the wire which projects into the rear end of the toy being rotatably mounted, a motor in the toy body geared to said wire for rotating the same and thereby causing the animal to simulatedly roll over on the floor, the head of the toy being higher than the body and thereby causing the toy to change direction as it rolls on the floor.
20. A toy simulating an animal body, wheels at the bottom of said body, a bent wire projecting from the body and simulating a tail, the end of the wire which projects into the toy being rotatably mounted, said wire clearing the body but not the floor during complete relative rotation, a motor in the body geared to drive the aforesaid wheels, and also geared to rotate the aforesaid wire in order to cause the animal to simulatedly roll over on the floor.
25. A toy simulating an animal body, wheels at the bottom of said body, a wire projecting from the rear end of said body and bent to a sideward position, said wire simulating a tail, the end of the wire which projects into the rear end of the toy being rotatably mounted, said wire clearing the body but not the floor during complete relative rotation, a motor in the toy body geared to drive the aforesaid wheels, and also geared to rotate the aforesaid wire to cause the animal to simulatedly roll over on the floor, the gearing leading to the wire being so arranged as to provide an intermittent rolling action.
30. A toy simulating an animal body, wheels at the bottom of said body, a wire projecting from the rear end of the body and bent to a sideward position, the end of the wire which projects into the rear end of the toy being rotatably mounted, said wire simulating a tail and being so shaped that it clears the body but not the floor when rotated, a motor in the body geared to drive the aforesaid wheels, and also geared to rotate the aforesaid wire to cause the animal to simulatedly roll over on the floor, the gear train leading to the wire providing an intermittent rolling action, so that the toy repeatedly alternately runs for a distance and rolls over, the head of the toy being higher than the body and thereby causing the toy to change direction as it rolls on the floor.
35. A toy simulating an airplane having a fuselage, wings projecting therefrom, projections facilitating sideward rolling over of the airplane, a wire projecting from the rear end of the fuselage and bent sidewardly, the end of the wire which projects into the rear end of the toy extending longitudinally of the toy and being rotatably mounted, a motor in the toy body geared to said wire for rotating the same and thereby causing the airplane to roll over on the floor, the forward part of the toy being larger in transverse direction than the rear part of the toy thereby causing the toy to greatly change its direction as it rolls on the floor.
40. A toy simulating an airplane having a fuselage, wings extending therefrom, a wheeled undercarriage projecting therebeneath, and a projection thereabove, the projections facilitating sideward rolling over of the airplane, a wire projecting from the rear end of the fuselage and bent sidewardly and then forwardly, the sidewardly bent part being long enough for the wire to clear the tail of the airplane during complete relative rotation of the wire and the airplane, the forwardly bent part extending outwardly somewhat in the approximate direction of the tip of the wing at one side, the end of the wire which projects into the rear end of the toy extending longitudinally of the toy and being rotatably mounted, and a motor in the toy body geared to said wire for rotating the same and thereby causing the airplane to roll over on the floor.
45. A toy simulating an airplane comprising a fuselage, wings extending therefrom, a wheeled undercarriage projecting therebeneath, a projection thereabove, the projections facilitating sideward rolling over of the airplane, a wire projecting from the rear end of the fuselage and bent sidewardly and then forwardly, the sidewardly bent part being long enough for the wire to clear the tail of the airplane during complete relative rotation of the wire and the airplane, the forwardly bent part extending in such direction as to lie approximately flat on the floor when the airplane rolls over, the end of the wire which projects into the rear end of the toy extending longitudinally of the toy and being rotatably mounted, a motor in said toy body geared to drive the aforesaid wheels and also geared to rotate the aforesaid wire to cause the airplane to simulatedly roll over on the floor.
50. A toy simulating an airplane comprising a fuselage, wings extending therefrom, a wheeled undercarriage projecting therebeneath, and a projection thereabove, the projections facilitating sideward rolling over of the airplane, a bent wire projecting from the rear end of the fuselage and bent sidewardly, the bent end of the wire clearing the airplane for complete relative rotation, the end of the wire which projects into the rear end of the toy extending longitudinally of the toy and being rotatably mounted, a motor in said toy body geared to drive the aforesaid wheels and also geared to rotate the aforesaid wire to cause the airplane to simulatedly roll over on the floor, the gear train leading to the wire being so arranged as to provide an intermittent rolling action so that the toy repeatedly alternately runs for a distance and rolls over.
55. A toy simulating an airplane comprising a fuselage, wings extending therefrom, wheels projecting therebeneath, and a projection thereabove, the projections facilitating sideward rolling over of the airplane, a wire projecting from the rear end of the fuselage and bent sidewardly, the end of the wire which projects into the rear end of the toy extending longitudinally of the toy.

- of the toy and being rotatably mounted, a motor in said toy body geared to drive the aforesaid wheels and also geared to rotate the aforesaid wire to cause the airplane to simulatedly roll over 5 on the floor, the teeth in a part of the gear train leading to the wire being cut away or mutilated to provide an intermittent rolling action so that the toy repeatedly alternately runs for a distance and rolls over, the forward part of the toy being 10 larger in transverse direction than the rear part of the toy thereby causing the toy to greatly change its direction as it rolls on the floor.
19. A toy comprising a toy body, wheels at the bottom of said body, a bent wire reaction member outside of said body connected to a shaft projecting from the body, a motor in said body for driving the aforesaid wheels and the aforesaid shaft, said reaction member being so positioned relatively to the shaft that it bears 20 against the floor and clears the body during complete rotation of the body relative to the reaction member, the gear train leading to the shaft including a mutilated gear driven by the motor and meshing with a driven gear for driv- 25 ing the shaft, means to lock the shaft against rotation during the dwell period of the driven gear, the rotative relationship of the parts being such that the reaction member is supported off the floor and the running wheels remain on the 30 floor during the dwell period of the reaction member.
20. A toy comprising a toy body, wheels at the bottom of said body, a bent wire reaction member outside of said body connected to a shaft pro- 35 jecting from the body, a motor in said body for driving the aforesaid wheels and the aforesaid shaft, said reaction member being so positioned relative to the shaft that it bears against the floor and clears the body during rotation of the 40 body, the gear train leading to the shaft including a mutilated gear driven by the motor and meshing with a driven gear for driving the shaft, the mutilated gear having teeth on a part of its periphery adequate to produce approximately 45 one revolution of the shaft, the remainder of the periphery being of such radius as to bear against and lock the driven gear against rotation during the dwell period of the driven gear, the rotative relationship of the parts being such that 50 the reaction member is held off the floor and the running wheels remain on the floor during the dwell period of the reaction member.

21. A toy comprising a toy body, wheels at the bottom of said body, a bent wire reaction member at one side of said body connected to a shaft projecting from one end of the body and extending longitudinally of the same, said reaction member and said body clearing one another during complete relative rotation of said member and said body, a motor in said body for driving the aforesaid wheels and the aforesaid shaft, the gear train leading to the shaft includ- 10 ing a mutilated gear driven by the motor and meshing with a driven gear for driving the shaft, the mutilated gear having teeth on a part of its periphery adequate to produce approximately one revolution of the shaft, means to lock the shaft against rotation during the dwell period of the driven gear, the rotative relationship of the parts being such that the reaction member is supported off the floor and the running wheels remain on the 15 floor during the dwell period of the reaction member, whereby the toy repeatedly alternately rolls over and runs for a distance, the toy being unimpeded by the reaction member when running. 20
22. A toy comprising a toy body, wheels at the bottom of said body, a bent wire reaction member at one side of said body connected to a shaft projecting from one end of the body and extending longitudinally of the same, said reaction member and said body clearing one another during com- 25 plete relative rotation of said member and said body, a motor in said body for driving the aforesaid wheels and the aforesaid shaft, the gear train leading to the shaft including a mutilated gear driven by the motor and meshing with a driven 30 gear for driving the shaft, the mutilated gear having teeth on a part of its periphery adequate to produce approximately one revolution of the shaft, the remainder of the periphery being of such radius as to bear against and lock the driven 35 gear against rotation during the dwell period of the driven gear, the rotative relationship of the parts being such that the reaction member is held off the floor and the running wheels remain on the floor during the dwell period of the reaction member, whereby the toy repeatedly alternately rolls over and runs for a distance, the toy being unimpeded by the reaction member when running. 40
